[57] **CLAIM**

The ornamental design for a pregnancy test kit, as shown and described.

DESCRIPTION

FIG. 1 is a top, front perspective view of a pregnancy test kit, showing my new design;

FIG. 2 is a top plan view thereof;

FIG. 3 is a front elevational view thereof;

FIG. 4 is a side elevational view thereof;

FIG. 5 is a side elevational view thereof, opposite that shown in FIG. 4;

FIG. 6 is an exploded top perspective view thereof; and

FIG. 7 is a top perspective view of the bottom portion of the kit with utensils removed.
